UNITED STATES PATENT OFFICE.

RICHARD U. CHADWICK, OF PHILADELPHIA, PENNSYLVANIA.

DRYING-CYLINDER.

SPECIFICATION forming part of Letters Patent No. 693,233, dated February 11, 1902.

Application filed June 5, 1901. Serial No. 63,250. (No model.)

To all whom it may concern:

Be it known that I, RICHARD U. CHADWICK, a citizen of the United States, residing in Philadelphia, Pennsylvania, have invented 5 certain Improvements in Drying-Cylinders, of which the following is a specification.

My invention relates to certain improvements in cylinders or cans heated by steam for drying any material—such as warps, cloth, 10 paper, &c.—passed over their outside surface, and more particularly to improved means for removing condensed water from the inside of said cylinders.

The object of my invention is the provision 15 of devices which will rapidly and certainly remove water from the interior of a drying-cylinder as rapidly as it is formed, irrespective of the speed of rotation of the cylinder. This object I attain as hereinafter set forth, 20 reference being had to the accompanying drawings, in which—

Figure 1 is a sectional elevation of my improved form of drying-cylinder. Fig. 2 is a side view of one end of the cylinder. Fig. 3 25 is a sectional view of the head of the old form of cylinder, showing my invention applied thereto. Fig. 4 is a side view of a cylinder-head provided with scoop-tubes for removing water from the cylinder irrespective of its direction of rotation. Fig. 5 is a side view of 30 one of the bracing partitions shown in Fig. 1. Fig. 6 is another form of the same modified for rotation of the cylinder in either direction. Fig. 7 is a plan view, partly in section, showing 35 the form and construction of the double scoop-tubes shown in Fig. 4; and Fig. 8 is an enlarged detail view of a portion of one of the scoop-tubes.

In the drawings, A is a cylinder which in 40 connection with a number of others is designed to be used for drying lengths or pieces of cloth, warp, paper, &c., passed over its outside surface. This cylinder has heads B B', each provided with a hollow trunnion b b', 45 made to turn in suitable bearings in a machine of any well-known form. Through one of these trunnions, as b', steam is made to enter the interior of the cylinder, and the other, b, is connected to a suitable drain-pipe 50 (not shown) for carrying off the water discharged.

The head B has cast integral with it a tube

b² of the form best shown in Fig. 2, which communicates with the hollow trunnion b. As seen in this figure, the said tube or conduit starts tangent to the curve of the periphery of the cylinder-head and for the first part of its length departs from this curve very slightly. It, however, gradually changes its direction more rapidly until it has reached 55 the center of the cylinder, where it communicates with the hollow trunnion through a curved section, as shown in Fig. 1 of the drawings. By this construction I avoid the angular form of conduits hitherto found in 60 devices of this class, providing for a free and unobstructed flow of water and compelling the same to make no sharp changes of direction. It will be seen from Fig. 1 that at its beginning or intake end this tube b² is comparatively long and narrow in cross-section, 65 while as it extends toward the outlet it becomes nearly circular in cross-section and of very much less cross-sectional area, the latter finally becoming equal to that of the opening 70 through the trunnion. If desired, this channel-piece or conduit may be made as a separate piece, as shown at b³ in Fig. 3, its inner end being turned in a right-angle curve and entering the trunnion. This form is of particular service in equipping old machines, as 75 it can be put in place of any former device and its front edge b⁴, fastened by rivets or solder to the inside surface of the drying-cylinder.

When it is desired to run the cylinder alternately in opposite directions, a form of tube construction is employed similar to that illustrated in Figs. 4 and 7. These tubes b⁵ have the same shape of curve as the conduit shown 80 in Fig. 2, but form channels entirely independent of each other all the way to their outlet at the other end of the trunnion, this construction being employed to prevent water collected by one tube from flowing into the 85 other instead of being discharged through the said trunnion. It will be seen that where the two pipes enter the trunnion they merge or empty into a single pipe b⁶, but the two passages are still maintained independent by a 90 partition b⁷.

In order to properly drain the tubes when the cylinder is out of operation, small triangular openings b⁸ are formed in the convex

side or bottom thereof, these being made as clearly illustrated in Fig. 8. The water normally flowing through the tube in the direction indicated by the arrow is made to pass over these openings by means of the upwardly-projecting tongues b^2 , while as soon as the cylinder ceases to move any water at that time in the curved part of the tube freely passes under said tongues and out of the openings, thus draining the tube in any position of the cylinder.

In drying-cylinders of any length it is necessary to provide interior ring stays or braces, ordinarily known as "blocks," there being two of these, C C', in the cylinder shown in Fig. 1, and in order that the water of condensation may flow freely from one end of the cylinder to the other openings $c c'$ are made in these rings. Ordinarily when the cylinder is rotated rapidly the said stays or rings would cut through the water, not allowing sufficient time for it to pass through these openings, and in view of this I provide vanes or guides $c' c'$ to assist the flow of said water. These vanes are inclined at an angle both to the axis of the cylinder and to the plane of the stay C, a vane being placed at one edge of each hole or opening c , thereby collecting a quantity of water and forcing it toward and through the hole. I preferably attach one edge of each vane to the inside surface of the drying-cylinder, thereby making them act as lateral stays to the stiffening-ring and causing them to assist in supporting said cylinder against a possible pressure either from the inside or outside thereof. These vanes preferably extend on both sides of the plane of the ring-stays C, and, in addition to their action by which water is directed toward and through the openings c , also act to throw the water away from the ring C after it has passed through the said openings. It will, however, be understood that I may, if desired, use the vanes or guides $c' c'$ on one side only of the ring C without departing from the main idea of my invention. By this means a clear space is made for the water delivered through one of the openings c by the next following vane, this fresh volume freely passing through the said opening without interference or choking from the water previously discharged, thus materially increasing the rapidity of the flow of the water toward the end of the cylinder, the ring-stay C, with its vanes, assisting the flow rather than retarding it.

In order to run the cylinder in both directions and discharge the water toward the outlet end, as before, I preferably use a construction similar to that shown in Fig. 6 and at 60 C' in Fig. 1, where one-half of the collecting-vanes c' are inclined in one direction and the others are oppositely inclined, it being understood that one cylinder ordinarily contains but one of the two types of brace or block described.

It will be seen that in the form of conduit b^2 and of ring stays or blocks C described

above and shown in the figures a result is obtained not possible with other forms of apparatus in use. The high speed at which 70 modern drying machinery is operated requires some device which shall collect and expel the water of condensation in spite of the increased centrifugal force. The gradual curve of the first part of my improved conduit makes it possible to collect and to start toward the center the water at the lowest part or bottom of the cylinder, and as the rotation of said cylinder continues and the curve of the tube becomes more pronounced the 80 said water flows toward the center with an increased velocity and out through the trunnion irrespective of the speed of the cylinder.

It is to be noted that by the use of a closed collecting tube or conduit at the end of my 85 drying-cylinder the flow of water through the same is materially aided by the steam-pressure within the cylinder, this acting to force the water through said collecting-conduit with a greater or less degree of intensity, depending upon the pressure of said steam. In addition to this advantage noted the closed form of conduit makes it impossible for the water once collected to return to the cylinder while the same is in motion, preventing 95 splashing or throwing around of said water, with the consequent danger of sudden condensation of steam and possible collapse of the cylinder.

I claim as my invention—

1. A drying-cylinder in combination with a curved conduit for removing water from the interior of the cylinder, the said conduit having in it drainage-openings provided with deflectors whereby water is prevented from 105 passing through said openings when the cylinder is rotated, substantially as described.

2. A drying-cylinder revolvably supported on tubular trunnions, closed curved conduits connected to one of the trunnions and constructed to collect and remove water from the cylinder, said trunnion being provided with means to prevent communication between the conduits, said means extending to the outer or discharge end of the trunnion, substantially as described.

3. A drying-cylinder revolvably supported on tubular trunnions, closed conduits curved in opposite directions connected to one of the trunnions and constructed to collect and remove water irrespective of the directions of rotation of the cylinder, said trunnion being constructed to prevent communication between the conduits to the outer or discharge end of said trunnion, substantially as described.

4. A drying-cylinder having tubular trunnions, curved conduits within the cylinder communicating with one of said trunnions, said conduits being joined, a section common 130 to both being provided with a partition extending through the trunnion to the outer or discharge end of the same, whereby water is prevented from flowing from one conduit to

the other as the cylinder is revolved, substantially as described.

5. A drying-cylinder supported on tubular trunnions, one of said trunnions being divided to form two channels, a closed curved conduit connected to each of said channels, said conduits curving in opposite directions and being constructed to collect and remove water from the cylinder irrespective of the 10 direction of rotation of said cylinder, substantially as described.

6. A drying-cylinder having within it a stiffening-ring provided with openings for the 15 passage of water, relatively short inclined vanes extending on both sides of said stiffening-ring, said vanes being constructed to guide water toward and through said openings, with means for finally removing water from the cylinder, substantially as described.

20 7. A drying-cylinder having within it a stiffening-ring, openings therethrough to allow of the passage of water, inclined vanes for said openings extending on both sides of the stiffening-rings constructed to guide water toward

and through the same, a number of said vanes 25 being inclined oppositely to the others whereby water is delivered through the openings in the ring irrespective of the direction of rotation of the cylinder, substantially as described.

8. A drying-cylinder having within it a stiffening-ring provided with openings for the passage of water, inclined vanes extending on both sides of the stiffening-ring, constructed to guide water toward and through said openings, said vanes being secured to the inside 30 surface of the cylinder as well as to said stiffening-rings, and being placed at relatively frequent intervals along the entire circumference of the ring, thereby acting as lateral 35 stays to said ring, substantially as described.

In testimony whereof I have signed my name to this specification in the presence of two subscribing witnesses.

RICHARD U. CHADWICK.
